DESIGN FOR A BRACELET

James C. Krutz, Charleroi, Pa., assignor to National Steel Fabric Company, Pittsburgh,
Pa., a corporation of Pennsylvania

Application May 11, 1946, Serial No. 129,625

Term of patent 3½ years

(Cl. D45—4)

To all whom it may concern:

Be it known that I, James C. Krutz, a citizen of the United States, residing at Charleroi, in the county of Washington and State of Pennsylvania, have invented a new, original, and ornamental Design for Bracelets, of which the following is a specification, reference being had to the accompanying drawing, forming part thereof.

The figure is a perspective view of a bracelet showing my new design.

I claim:

The ornamental design for a bracelet, as shown.
